COOLING AND DISPENSING APPARATUS
FOR KEGS

Edward C. Clifford, Sand Lake, N. Y.

Application August 11, 1934, Serial No. 739,459

12 Claims. (CI. 225—40)

This invention relates to cooling and dispensing devices for barrels and more particularly refers to improvements in devices of the type where a barrel or keg, from which liquid is to be withdrawn, is supported within a casing provided with means for cooling the contents of the barrel or keg.

In a patent entitled, "Barrel supporting and cooling device", No. 1,957,199, issued to me on May 1, 1934, reissued November 6, 1934, No. Re. 19,361, I have described and claimed a support for a barrel, consisting of two sections hinged together along a longitudinal edge, adapted when closed to form a housing partially at least enclosing the peripheral portion of the barrel. The inner surface of said housing is spaced a certain distance from the surface of the barrel, providing a space adapted to receive a network of conduits for the passage of the cooling medium.

The primary object of the present invention is to provide a cooling device for barrels, embodying the invention forming the subject of my above mentioned patent and also providing a supporting cabinet structure for the cooling device, forming with it a completely self-contained unit, equipped with all the necessary means for producing the circulating cycle of the cooling medium and for maintaining predetermined conditions within the barrel; at the same time supporting the barrel at a height convenient for the dispensing of liquid directly therefrom.

Another object of the invention is to provide a cooling and supporting unit for barrels, of a novel and compact construction, said unit being complete with all necessary cooling equipment and being preferably of a portable character and adapted to be placed in any convenient available relatively small space.

A further object is to provide a device of the character specified, adapted to support two barrels, so that at all times one barrel may be on tap while the other is being pre-cooled, said device comprising the necessary cooling equipment and means for reversing the connections of the cooling medium so as to always cause it to expand first around the barrel from which liquid is being dispensed, where a lower temperature is required.

A still further object is to provide, in a supporting and cooling device, adapted to hold two barrels, one for pre-cooling and the other for dispensing liquid, means mounted on the device itself, making it possible to handle barrels for placement in or removal from their cooling and dispensing position, so as to render the device

absolutely independent of all outside means for its operation.

Other objects and advantages of the present invention will more fully appear as the description proceeds and will be set forth and claimed in the appended claims.

My invention is illustrated by way of example in the accompanying drawings, in which:

Fig. 1 is a vertical section of the upper portion of my device, forming the casing for receiving and cooling a barrel;

Fig. 2 is a plan view of said casing, with the top section separated from the lower section and with cooling coils permanently affixed in each section;

Fig. 3 is a detail view of portions of conduits used for circulating cooling medium;

Fig. 4 is a front view in elevation of another device with parts broken away to show the interior of the cabinet portion thereof;

Fig. 5 is a side view in elevation thereof, with parts broken away to show the arrangement of various elements within the cabinet portion thereof;

Fig. 6 is a detail sectional view through line 6—6 of Fig. 5;

Fig. 7 is a front view in elevation of a device embodying my invention, adapted to support and cool two barrels at the same time, said device being also provided with means for handling the barrels;

Fig. 8 is a fragmentary vertical longitudinal section through the top of the cabinet portion of the device shown in Fig. 7, illustrating the means for reversing the connections for the cooling and servicing of the two barrels;

Fig. 9 is a detail side view in elevation of the control valve shown in Fig. 8;

Fig. 10 is a cross section in an enlarged scale through line 10—10 of Fig. 9;

Fig. 11 is a cross section in an enlarged scale through line 11—11 of Fig. 9; and

Fig. 12 is a fragmentary horizontal section through line 12—12 of Fig. 1.

Referring to Figs. 1, 2, 3, upper and lower sections of the casing are indicated at 10 and 11 respectively. The top section 10 comprises a peripheral wall 12 to the ends of which are secured end walls 14 and 15. The lower section 11 is provided with a peripheral wall 16, similar in configuration to the wall 12 and with end walls 17 and 18. The end walls 14, 15, 17 and 18 have their inner edges of substantially semi-circular configuration, as at 19, so that when the sections are closed, as in Fig. 4, annular rings will be 55

formed of pairs of end walls at the respective ends of the sections, with the walls 14 and 17 as one pair and the walls 15 and 18 as another pair.

The longitudinal walls and the end walls of the two sections may be constructed of wood, although it is to be understood that other materials of suitable nature can be used, and preferably these walls are to be made of, or covered with, some stain and acid resisting metal, such as, for example, stainless steel.

Hinges 35 are provided to connect adjacent longitudinal edges of the sections, while locking devices 36 serve to lock the sections together. Spaced from the interior surface of the wall 12 is a liner 19', of suitable material, such as metal, having a curvature conforming to the curvature of the barrel, said liner extending between the ends 14 and 15 to which it can be secured. By this arrangement of outer wall and liner, a space is provided in which is placed insulating material 20, which may be any suitable material having good thermal insulating properties. The lower section 11 is provided with a liner 21, similar to liner 19 and a space in which is placed insulating material 22, similar to insulating material 20.

Positioned in the lower section 11 is a network of conduits 25, so interconnected by means of elbows 26 that a continuous passage is provided from one extreme conduit to the other for the circulation of suitable cooling medium. These conduits 25 extend immediately above the liner 21 in such fashion as to provide a network which conforms to the outline and the shape of the liner 21, and, of course, to the surface of the barrel. The network of conduits can be permanently secured in lower section 11 in any desired fashion.

The upper section is similarly equipped with a network of conduits fastened within said section 40 in the same fashion as the lower network is fastened in the lower section.

All of the conduits are provided with fins 44, in the nature of thin strips of metal extending around each conduit in spiral fashion along the length thereof. These fins aid in cooling articles supported within the two sections.

An inlet pipe 45 leads from suitable compressing and circulating mechanism through a tube 49, downwardly extending from one end of the lower section, into communication with one extreme conduit in the network of conduits in the lower section 11. The other extreme conduit of this network is connected by means of a flexible tube 46 to one extreme conduit of the upper network. The other extreme conduit of this network is connected to a pipe 47, which leads back to the hinged side of the section and is connected to a flexible tube 48, which also passing through the tube leads back to the compressing and circulating apparatus.

Thus a complete circulation of cooling medium first through the lower network and then through the upper network can be accomplished.

To protect the conduits of the lower network, use is made of a bar 50, fastened to the end wall 18 and extending longitudinally of the lower section 11 to the other end wall 17 thereof, at which point it may be bent downwardly, as at 51, to be secured to said wall 17. This protecting bar is in a slightly higher position than the network of conduits, so that it will prevent contact between the barrel and these conduits.

Since condensed moisture will collect within the casing, it is necessary to provide means for withdrawing the same, especially when the device

is to be defrosted. A drain 52 communicates with the lowest point of the liner 21 and extends upwardly through the end wall 17. A valve can be provided therefor, if desired.

Strips of good thermal insulating material 60 are secured to each edge of the walls of the sections which contact with other edges, or which contact with the barrel positioned in the casing, to insure that there will be substantially no circulation of outside air in the chilled space when a barrel is in position to be cooled. The material 60 may be of any suitable character, such as, for example, sponge rubber, so long as it possesses good thermal insulating properties.

The structure so far described, per se, forms the subject of my other patent above referred to and its various novel features have been described and claimed therein.

As stated in the premises, the present invention is more particularly directed to a self-contained structure of which the cooling casing just described forms a part, said structure being complete with a suitable cabinet forming a support for the casing, the space in said cabinet being utilized for housing all the elements necessary for compressing and circulating the cooling medium, as well as a supply of carbon dioxide to be used in connection with carbonated beverages.

In Figs. 4 to 6 I illustrate a single unit type of cooling and supporting device embodying my invention, in which 70 designates a cabinet-support, having a front frame 71 and a rear frame 72, connected by side braces, such as 73, 74, 75, said front and rear frames extending upwardly as at 76, 77, to form a front and a rear support for the casing, the outline of the upper surface of said supports following the outline of the lower part of the casing and the rear support 77 being higher than the front support 76, so that the casing together with the barrel therein contained will be tilted sufficiently to insure proper draining of the contents thereof through the spigot S, which is arranged to be at the lower-most possible point of the barrel, when said barrel is positioned in the lower section of the casing.

The resulting structure is provided with a bottom 78, a top 79, a front panel 80, two side panels 81, 82, and a rear panel 83. Said panels are preferably provided with transversal slots, such as shown at 84, in order to provide ventilation for the interior of the chamber 85 formed thereby. The top 79 of said chamber is preferably vertically spaced from the lower side of the casing, partly for the sake of appearance and partly in order to set in evidence the fact that no pipes from a remote cooling plant are used to supply the beer to the barrel. The independent and portable character of the device is further emphasized by providing the bottom of the cabinet with casters, such as 86, which make it possible for the device to be moved to any convenient place.

The front support 76 is provided with a frontwardly extending supporting frame 87, on which can be placed a pan 88, provided with a removable perforated tray 89, said pan remaining directly under spigot S and drain 52, as Fig. 5 clearly shows. Said pan will collect all the liquid dripping from the spigot and drain, as well as the excess foam that should overflow or be combed off the top of the glass placed upon tray 89, when liquid is discharged through spigot S. Since pan 88 is removable, the liquid therein collected can be disposed of from time to time.

Chamber 85 provides the necessary space for 75

housing the compressor 90, the electric motor 91, driving said compressor by means of a belt 92, and the condenser 93, the motor 91 being connectible to any available wall socket by means 5 of a plug 94, attached to a flexible conductor 95. It will be observed that the condenser 93 is placed directly behind the motor, so that said motor can be equipped with a fan 91', directing a stream of cooling air against said condenser.

10 As Fig. 4 clearly shows, the discharge end of the compressor is connected to the inlet end of the condenser by a tubular connection 96, while the discharge end of the condenser is connected to the network of conduits in the lower section 15 by pipe 45, pipe 48 leading from the discharge end of the network of conduits in the upper section to the suction end of the compressor, thus completing the circulating cycle of cooling medium. As stated, pipes 45, 48, are led to the in-20 side of the lower section through a tube 49, effectively concealing all tubular connections.

The device is particularly intended for use in connection with kegs containing carbonated beverages, especially beer. It is well known that the 25 problem of dispensing carbonated beverages, particularly beer, at the desirable low temperature, is much more involved than that of dispensing cold water.

Furthermore, beer presents certain other difficulties, in view of the necessity of preventing 30 fermentation, as well as the formation of excess foam, resulting in extreme cases in the delivery of so-called "wild beer". At the same time, beer and other carbonated beverages should be maintained with a sufficient amount of carbon dioxide in solution, preventing them from becoming "flat" and should be delivered at a pressure sufficient to cause a certain agitation liberating bubbles of gas therefrom, with the formation of 35 a certain desirable amount of foam or "collar".

Carbonated beverages generally can be maintained in the desirable palatable condition, due to the presence of carbon dioxide in solution, by connecting the container to a source of carbon 40 dioxide, said gas replacing the liquid as it is drawn, and excluding the presence of air; said carbon dioxide being maintained at a predetermined pressure, such as may be found best according to the nature of the liquid itself and the 45 temperature and other conditions under which it is dispensed from the container.

In this connection, it is necessary to bear in mind that a chilled carbonated liquid will hold 50 in solution a greater quantity of carbon dioxide than the same liquid at room temperature, so that an excessive pressure need not be maintained within the container in order to insure the proper content of carbon dioxide in the liquid dispensed therefrom.

60 In the case of beer, it is also particularly desirable to maintain a relatively low pressure within the keg so that the beer may be delivered without excessive agitation and with the correct amount of foam or "collar", and it is also essential that the pressure remain absolutely uniform. It is also, of course, highly desirable that the beer be drawn directly from the keg, in order to prevent its coming in contact with metallic surfaces which impart to it an objectionable taste.

70 In most installations for dispensing beer, the kegs are placed somewhere in the basement and the beer is forced by pressure of the carbon dioxide supplied to the kegs to the dispensing apparatus proper, which is generally placed on a 75 counter or bar on the floor above. The dispens-

ing apparatus is provided with cooling coils, through which the beer is caused to flow before reaching the outlet and during this process it acquires a disagreeable metallic taste. Furthermore, in order to force the beer from the basement to the floor above it is necessary to supply the carbon dioxide at relatively high pressure and this, as stated, results in the formation of excess foam which must be combed off the glass and which constitutes a material source of loss. 10

My device provides an ideal way of satisfactorily meeting all the above mentioned conditions. It provides an effective arrangement for cooling the beer or other liquid right in the keg and for dispensing it on tap therefrom, while cold, that is, in the best condition for retaining in solution a sufficient amount of carbon dioxide, without maintaining an excessive pressure within the keg. Furthermore, the necessity of maintaining an excessive pressure within the keg is also done away with, due to the fact that the liquid is dispensed from its original container and, therefore, does not have to be forced from a lower to a higher level. The resulting combination of low temperature and low pressure will cause the liquid to be charged with the proper amount of gas and to be delivered without excessive agitation, with its flavor unimpaired by contact with metallic surfaces. 15 20 25

In order to realize these conditions, I also provide space in chamber 85 of the cabinet for the placement of a drum 97, containing carbon dioxide under pressure, said drum being as usual provided with a regulating valve 98, equipped with a pressure gauge 99. A tube 100 leads from said regulating valve and through tube 49 to the inside of the casing, the outer end of said tube being equipped with a plug 101, the stem of which, 102, can be forced in the opening usually provided in the bung 103 at the top of the keg. Plug 101 is preferably equipped with a valve 104, by means of which the flow of carbon dioxide can be cut off when the plug is withdrawn from an empty keg, previous to its removal and replacement of another full keg. 30 35 40 45

As stated, in connection with beer and other carbonated beverages, it is desirable not only to maintain a relatively low pressure within the keg but also to insure a condition whereby said pressure will be uniformly maintained. Although the regulating valve 98 makes it possible to supply the carbon dioxide from the drum to the keg at the desired pressure, this does not prevent the pressure from rising within the keg, due to the liberation of gas contained in the liquid itself. I accordingly provide in the circuit of tube 100, an adjustable relief valve, such as shown at 105 in Fig. 5, which will be set at the same pressure as the regulating valve 98 and which will cause any excess gas within the keg to be discharged therefrom. 50 55 60

Due to the fact that it requires some time to chill liquid within a keg, the use of an apparatus such as described generally requires an auxiliary pre-cooling installation, in which kegs are stored and maintained at a relatively low temperature, so that when placed on the supporting and dispensing device the liquid contained therein will be ready to be dispensed in short order. Full kegs ordinarily weigh about two hundred pounds or thereabout and, therefore, their conveyance from the pre-cooling chamber to the dispensing device will necessitate the use of traveling hoist facilities, for instance, a trolley hoist. 65 70 75

In small installations it is desirable that the

device be complete in itself also in respect to pre-cooling and handling of the kegs and, therefore, I have devised the type of apparatus illustrated in Figs. 7 to 11. The same consists of a cabinet-support 106, within which is located the compressing and circulating plant for the cooling medium, the upper part 107 of said cabinet-support being formed to receive two casings, 108, 109, side by side, said casings alternately serving as pre-cooling and cooling and dispensing housings for kegs 110, 111, placed therein. Furthermore, said cabinet-support is preferably provided with a crane 112, of the job or goose-neck type, rotatable about a vertical axis by means of a crank lever 113. Said crane is provided with a suitable hoisting mechanism, such as indicated at 114, including cable 115, running between upper block 116 and a lower block 117, the lower block being provided with two gripping arms 118, 119, adapted to grip 20 the ends of the keg 120, as shown in dotted lines at 118' and 119' in Fig. 7.

By virtue of this arrangement it is, therefore, possible to raise the full keg from the floor to a level above the lower section of the open casing and to turn it 90° to the right or to the left in order to lower the keg in position. The new keg thus placed in position will be pre-cooled while the liquid in the other keg is being dispensed, and when said other keg will have been 30 emptied the keg which was previously pre-cooled will be used for dispensing and the empty keg will be replaced by a new full keg which in its turn will be pre-cooled.

It is, of course, desirable to maintain the keg 35 from which liquid is being dispensed at the required low temperature and, therefore, the expansion of the gas used as a cooling medium should be caused to take place first in the network of conduits of the casing within which the dispensing keg is placed. It is, therefore, desirable to provide a suitable arrangement whereby the cooling medium is alternately caused to flow first through one casing and then through the other one.

An arrangement of this type is illustrated in detail in Figs. 8 to 10. In Figs. 7 and 8, 121 designates the top of the cabinet, 122 the tube for the various gas conductors leading to casing 108 and 123 the tube for the various gas conductors leading to casing 109. 124 designates a multiple-way valve inserted in the circuit of the cooling medium, said valve being actuated by a hand lever 125, the position of which inclined toward the left denotes that the cooling medium is caused to flow 50 first through the network of conduits of casing 108 at the left and then through the network of conduits of casing 109 at the right, so that 110 is the dispensing keg and 111 is the keg which is being pre-cooled.

Valve 124 comprises a valve casing 126, provided with inlet 127 for the cooling medium coming from the condenser and outlet 128 for the cooling medium returning to the compressor and two ports 129, 130, connected to one end of the 65 cooling coils within casing 108 and casing 109, respectively, by connections 131, 132. The other ends of said cooling coils are connected to each other across tubes 122, 123, by a tubular connection 133, shown in Fig. 8.

Within valve casing 126 is rotatably mounted a valve member 134, provided with two ducts 135, 136, adapted to connect inlet 127 and outlet 128 to ports 129, 130, respectively, when said valve member is in the position shown in full lines in 75 Fig. 10 and adapted to reverse the connections

when said valve member, being angularly displaced 90° in a counterclockwise direction, said ducts will be set in the position shown in dotted lines in said Fig. 10.

It is thus seen that by virtue of this arrangement the cooling medium reaching inlet 127 through pipe 137 will be caused to flow through connection 131 and the network of conduits of casing 108, then through tubular connection 133 it will be transferred to the network of conduits within casing 109, from which it will return to the compressor through connection 132, duct 136, outlet 128 and pipe 138.

When valve member 134 is set in its other extreme position, where ducts 135, 136 will acquire the positions 135', 136', shown in dotted lines, the cooling medium will be caused to flow first through the network of conduits within casing 109 and then through the network of conduits within casing 108.

When the pre-cooled keg is going to be used as the keg from which liquid will be dispensed, it is also necessary to direct thereto the carbon dioxide supplied by the drum. Therefore, valve casing 126 is also provided with an inlet 139 connected to the carbon dioxide drum by a pipe 140, an outlet 141, to which is connected a pipe 142, leading to the keg within casing 108 and an outlet 143 to which is connected a pipe 144 leading to the keg within casing 109. The valve member 134 is accordingly provided with a segmental chamber 145, from which extend two diametrically opposite ducts 146, 147, which will establish communication between said chamber 145 and outlets 141, 143, respectively, in the two positions of valve member 134. Thus, in the position shown in Fig. 11, the carbon dioxide coming from the drum is directed by duct 146 and pipe 142 to the keg within casing 108 and when the valve member will be turned 90° in a counterclockwise direction, the carbon dioxide will be directed to the keg within casing 109 instead.

Suitable thermostatic means (not shown) controlling the operations of the motor and compressor are, of course, provided in a well known manner.

It is thus seen that I provide a thoroughly self-contained apparatus complete with means for pre-cooling one keg, means for chilling a keg from which liquid is being dispensed, means for handling said kegs, means for compressing and circulating cooling medium, means for supplying carbon dioxide under the proper pressure to the keg from which liquid is being dispensed and means for reversing the connections for the flow of the cooling medium and the carbon dioxide respectively. Such an apparatus constitutes in itself a complete installation, making it unnecessary to provide a separate pre-cooling plant and hoisting and conveying devices between the pre-cooling plant and the cooling and dispensing device.

It is obvious that the constructional details of my invention can vary from those shown without departing from the inventive idea. The drawings will, therefore, be understood as being intended for illustrative purposes only and not in a limiting sense.

I accordingly reserve the right to carry my invention into practice in all those ways and manners which may enter, fairly, into the scope of the appended claims.

I claim:

1. A self-contained supporting and cooling device for barrels comprising, in combination, two

casings each adapted to receive and surround partially at least, the peripheral surface of a barrel, a network of conduits within each casing, adjacent the surface of a barrel housed therein, the two networks of conduits being interconnected, means within said structure for circulating cooling medium, and connections between said circulating means and said networks of conduits, causing the cooling medium to circulate first through the network of conduits of the casing housing a barrel from which liquid is to be dispensed, and then through the network of conduits of the other casing, for pre-cooling of the liquid within the barrel housed therein.

15 2. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, and 20 means inserted in said connections for selectively determining the sequence of flow of said medium through said two networks of conduits.

3. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, causing the cooling medium to circulate first through the network of conduits of the casing 35 housing a barrel from which liquid is to be dispensed, and then through the network of conduits of the other casing, for pre-cooling of the liquid within the barrel housed therein, a carbon dioxide container associated with said structure, 40 and a tubular discharge outlet therefor, adapted to be connected to the barrel from which liquid is to be dispensed.

4. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, a carbon dioxide container associated with said structure, a tubular discharge outlet therefor, 50 means inserted in said connections for selectively determining the sequence of flow of said cooling medium through said two networks of conduits, and means for selectively connecting said discharge outlet to one or the other barrel.

65 5. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, a carbon dioxide container associated with said structure, a tubular discharge outlet therefor, 70

ture, a tubular discharge outlet therefor, and valve means, inserted in said connections and discharge outlet, for selectively determining the sequence of flow of said cooling medium through said two networks of conduits, and for connecting 5 said discharge outlet to the barrel housed within the casing through the network of conduits of which the cooling medium is caused to flow first.

6. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, causing the cooling medium to circulate first through the network of conduits of the casing 10 housing a barrel from which liquid is to be dispensed, and then through the network of conduits of the other casing, for pre-cooling of the liquid within the barrel housed therein, and means, mounted on said structure, for hoisting 15 and handling barrels to be placed within said casings, or removed therefrom.

7. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, means inserted in said connections for selectively determining the sequence of flow of said medium through said two networks of conduits, and a 20 crane of the goose-neck type rotatably mounted 25 on said structure.

8. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, a carbon dioxide container associated with said structure, a tubular discharge outlet therefor, 30 valve means, inserted in said connections and discharge outlet, for selectively determining the sequence of flow of said cooling medium through said two networks of conduits, and for connecting 35 said discharge outlet to the barrel housed within the casing through the network of conduits of which the cooling medium is caused to flow first, and means indicating the position of 40 said valve means.

9. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said circulating means and said networks of conduits, a carbon dioxide container associated with said structure, a tubular discharge outlet therefor, 50

valve means, inserted in said connections and discharge outlet, for selectively determining the sequence of flow of said cooling medium through said two networks of conduits, and for connecting said discharge outlet to the barrel housed within the casing through the network of conduits of which the cooling medium is caused to flow first, and means, mounted on said structure for hoisting and handling barrels to be placed within said casings, or removed therefrom.

10. A self-contained supporting and cooling device for barrels comprising, in combination, two casings each adapted to receive and surround partially at least, the peripheral surface of a barrel, a network of conduits within each casing, adjacent the surface of a barrel housed therein, the two networks of conduits being interconnected, means within said structure for circulating cooling medium, connections between said 15 circulating means and said networks of conduits, a carbon dioxide container associated with said structure, a tubular discharge outlet therefor, valve means, inserted in said connections and discharge outlet, for selectively determining the sequence of flow of said cooling medium through said two networks of conduits, and for connecting said discharge outlet to the barrel housed within the casing through the network of conduits of which the cooling medium is caused to flow first, means indicating the position of said 20 valve means, and means, mounted on said structure, for hoisting and handling barrels to be placed within said casings, or removed therefrom.

11. A self-contained supporting and cooling device for barrels comprising, in combination, a

casing adapted to receive and snugly surround partially at least, the peripheral surface of a barrel, a network of conduits within said casing adjacent the position occupied by the surface of a barrel within said casing, a cabinet structure for supporting said casing, means within said structure for circulating cooling medium, connections between said circulating means and said network of conduits, and a tubular discharge member having an outlet terminal and an inlet terminal located within said cabinet and adapted to be connected to a high pressure gas container, said outlet terminal being arranged within said casing in position to be connected to the bung of such barrel.

15. 12. In a self-contained supporting and cooling device for barrels comprising a casing adapted to receive and snugly surround partially at least, the peripheral surface of a barrel, a network of conduits within said casing adjacent the position occupied by the surface of a barrel within said casing, a cabinet structure for supporting said casing, and means within said structure for circulating cooling medium, connections between said circulating means and said network of conduits, a tubular discharge member having an outlet terminal and an inlet terminal located within said cabinet and adapted to be connected to a high pressure gas container, said outlet terminal being arranged within said casing in position to be connected to the bung of such barrel, and a tubular enclosure for said connections and discharge member extending between said cabinet structure and the lower part of said casing.

EDWARD C. CLIFFORD. 35
